UNITED STATES PATENT OFFICE.

HERBERT E. DENNETT, OF BOSTON, MASS., ASSIGNOR TO THE DENNETT DENTAL NÁBOLÍ COMPANY, OF HARTFORD, CONN.

DENTAL COMPOUND FOR PREVENTING PAIN.

SPECIFICATION forming part of Letters Patent No. 232,807, dated October 5, 1880.

Application filed January 26, 1880. (Specimen.)

To all whom it may concern:

Be it known that I, HERBERT ENOS DENNETT, of Boston, in the county of Suffolk, State of Massachusetts, have invented a certain new and useful Improvement in Dental Compounds, of which the following is a description sufficiently full, clear, and exact to enable any person skilled in the art or science to which my invention appertains to make and use the same.

My invention relates to that class of dental compounds or preparations which are employed to prevent pain in filling teeth, or during the process of excavating or preparing the cavities to receive the filling; and it consists in a novel combination of ingredients, as hereinafter more fully set forth and claimed, by which a more effective article of this character is produced than is now in ordinary use.

As the structure or anatomy of the teeth is well understood by all practical dentists, a brief description of the same is all that is deemed necessary in order to show the nature of my improvement.

A tooth consists of three principal parts—viz., the enamel or outer coating, the dentine or body, and the pulp or center. Connected with the pulp and extending throughout the body are a series of minute and extremely sensitive nerves, which, when exposed to the air or brought into contact with foreign substances, cause more or less pain. Hence when decay takes place, and it becomes necessary to fill the cavity produced thereby, the pain caused by the instruments being brought into contact with the exposed nerves in excavating the cavity is sometimes very intense, and frequently interferes materially with the work of the dentist. To obviate this has long been the

study of the profession, use having been made of a great variety of articles designed to produce deadening or anodyne effects on the nerves of the tooth, such as oil of cloves, creosote, camphor, spirits of nitric ether, borax, carbolic acid, landanum, chloroform, alum, myrrh, tinctures of iron, chloral, morphia, carbonate of potassa, sulphate of zinc, chlorate of potassa, &c., and also compounds embodying more or less of these ingredients. Caustic preparations of arsenic, burnt alum, zinc, pot-

ash, acid, &c., have also been employed to kill or destroy the nerves; but, aside from the poisonous nature of some of the last-named articles and the great danger incurred in their use, it is now considered by nearly all scientific dentists very objectionable to destroy the nerves of the tooth when possible to avoid it.

In view of the foregoing I have for many years experimented constantly to discover a substance or compound that would produce, when directly applied, such an effect as to enable cavities to be properly excavated and filled without causing pain or killing or destroying the nerves of the teeth. These experiments have disclosed the following facts having direct relation to my present invention, viz: The body or dentine of the tooth is formed or built up of superposed layers composed of infinitesimal tubes, between which layers and in immediate contact with the nerves there are a series of exceedingly small flattened tubes or ducts filled with serum, or a thin watery fluid, and extending through from the enamel to the pulp. These ducts, while in their normal state, act as liquid telegraphs, so to speak, to convey along the line of the nerves the impulse or vibrations produced by the dental instruments used in excavating or preparing the cavity and filling the same, thus greatly increasing the sensitivity of the nerves, and rendering the operation much more painful.

By simply desiccating or drying the exposed surfaces in the cavity the pain may be lessened. It may also be reduced by means of powerful astringents and caustics; also, by the direct application of substances possessing obtundent properties, and by the use of anæsthetics or anodynes. As a desiccant, hot air has been employed with some success, being forced or injected into the cavity by means of a proper pump or instrument designed for that purpose; but as hot air can be brought into contact with the surface only, the relief afforded is not always certain and always but partial. For the same reason several of the substances hereinbefore enumerated may be properly termed "surface-desiccants," such, for instance, as burnt alum, carbonate of potassa, &c., their action being mainly superfi-

cial, as they possess very slight, if any, capillary or penetrative properties, their astrin-
gent or caustic action tending to greatly limit
their absorbent action when used as indi-
cated—an objection which applies with equal
force to various other metallic and vegetable
substances possessing absorbent, or absorbent
and astringent, properties which have been
tried for the same purpose.

10 I have found, therefore, that in excavating
and filling teeth an article designed to pro-
duce insensibility to pain by direct applica-
tion to the cavity should, in order to accom-
plish the desired results, possess qualifications
15 which do not pertain exclusively to any of the
substances named, or to analogous substances
or their compounds. I have also found that
at least three elements, acting wholly or in a
measure independently of each other, and pro-
20 ducing somewhat different results, are essen-
tial in a compound or preparation of this char-
acter, and also that a fourth may sometimes
be employed to advantage as auxiliary to the
others, to wit: first, a desiccant; secondly,
25 an obtundent; thirdly, an astringent; and,
fourthly, an anodyne. These elements should
also have certain peculiarities of their own,
viz: The desiccant should possess few or no
astringent properties, and should not act as a
30 caustic or escharotic. It should also be of
such a nature as to readily penetrate the tubes
or ducts of the dentine and absorb the fluids
contained therein. The obtundent should be
strictly what its name indicates, deadening
35 sensibility by coating and sheathing the ex-
posed nerves, producing at the same time a
soothing demulcent effect. The astringent
should be purely of an astringent nature with-
out caustic properties, and the anodyne one
40 that will have a prolonged action, or not be
readily evaporated or dissipated in use. It is
also equally important that none of these ele-
ments should, either by themselves or when
combined, operate to injuriously affect the
45 teeth or health.

My improved compound is believed to pos-
sess in a marked degree all of the essential
features mentioned, and is prepared as fol-
lows: Take of glycerine one fluid ounce; tan-
50 nic acid, two drams; chloral, four grains.
Mix thoroughly by rubbing up all of the in-
gredients in a mortar or other suitable vessel,
after which they must be strained or filtered
until clear. The glycerine should be of the
55 very best quality, free from water, lime, buty-
ric acid, chlorine, chloride of calcium, lead, sul-
phuric acid, sugar, and all other adulterations
or impurities. The tannic acid should also be
pure and of full strength, the white being best,
60 as it usually contains less gallic acid than the
yellow.

The proportions given in the above formula
may be varied, as desired, without departing
from the spirit of my invention, although I
65 prefer in all cases to use a saturated solution
of tannin and glycerine, the relative propor-

tions of the last-named ingredients in such a
solution being substantially as stated, or about
four parts of glycerine to one of tannin. The
amount of ordinary chloral required for one
70 and one-fourth ounce of the compound is one
grain; but I sometimes omit the anodyne en-
tirely, and at others increase this quantity to
five grains or more, or use butyl chloral in-
stead where a stronger anodyne is indicated.
75 Acetate of morphia and some other anodynes
may be substituted for the chloral, or used in
varying proportions therewith, but simple
chloral is deemed preferable. I also some-
times employ camphor in place of chloral, as
80 well as in combination with the same and the
other ingredients, the camphor and chloral be-
ing used in nearly equal quantities. The tannic
acid may also be substituted by sulphate of
zinc, sulphate of cadmium, and various other
85 astringents; but the tannin is far superior in
every respect to any similar article with which
I am familiar, being very powerful and en-
tirely harmless.

As glycerine possesses remarkable capillary
or penetrative powers and has an intense af-
finity for water, its peculiar value as a desic-
cant in this connection will be readily appre-
ciated. It rapidly penetrates the dentine, ab-
sorbing the contents of the tubes or ducts, and
95 also all moisture from the cavity, at the same
time serving as a perfect obtundent by sheath-
ing or coating the exposed nerves, thus com-
bining in itself two very essential features or
elements of my invention—to wit, an obtund-
ent and a desiccant. The glycerine also acts
100 as a vehicle by means of which the astringent
and anodyne are brought more speedily and
effectually into contact with the sensitive por-
tions of the tooth than is possible by any other
105 agent with which I am familiar.

Other oils or oily compounds may be used in
place of the glycerine, but are far less effectual
in nearly every respect. For instance, the hy-
drocarbon oils, both light and heavy, either
110 alone or in combination with oils of a different
nature, while possessing some of the charac-
teristics of glycerine, produce very unsatis-
factory results, so far as my observation and
experience have extended.
115

The method of using my improved compound
will readily suggest itself to any dentist with-
out explicit instructions in that respect. It
may be conveyed to the cavity as often as re-
quired before and during the operation of ex-
cavating by means of a small piece of punk
or cotton saturated in the solution and held
in any proper implement, or it may be ap-
plied in any other manner most convenient,
using about one drop at each application.
120 When prepared in accordance with the for-
mula the compound is too strong for use in
making the first applications to the tooth, and
should be diluted with distilled water until re-
duced to the proper strength to be borne by
125 the patient, the undiluted compound being
used for the later and final applications.

It will be obvious that the compound may be employed to prevent pain, not only in preparing the cavities and filling the same, but in numerous other operations on the teeth; also, that on account of its transparency it will not interfere with a free inspection of the work being done—a very essential feature in an article of this character.

Having thus explained my invention, what I claim is—

In a dental compound for preventing pain in excavating and preparing teeth for filling, the combination of glycerine, tannic acid, and chloral, substantially as set forth and specified.

HERBERT ENOS DENNETT.
